Francis M. Case
BY
T. J. W. Robertson

ATTORNEY.

UNITED STATES PATENT OFFICE.

FRANCIS M. CASE, OF DENVER, COLORADO.

SASH-FASTENER.

SPECIFICATION forming part of Letters Patent No. 312,251, dated February 17, 1885.

Application filed September 10, 1884. (No model.)

To all whom it may concern:

Be it known that I, FRANCIS M. CASE, a citizen of the United States of America, residing at Denver, in the county of Arapahoe and State of Colorado, have invented certain new and useful Improvements in Sash-Fasteners, of which the following is a specification, reference being had therein to the accompanying drawings.

- o This invention relates to certain new and useful improvements in that class of sash-fasteners which are designed to be attached to the top of the lower sash and to lock the upper sash to the lower one, and also lock both sashes to the window-frame at the side. In devices of this kind as heretofore constructed a separate device has been provided in order to lock the bolts that secure the sashes in the desired position.
- o The object of my invention is to provide a sash-fastener of this class in which the bolts shall be locked without the employment of a separate locking device; and to this end and such others as the invention may apply it consists in the peculiar combinations and the construction and arrangement of parts herein-after more fully described, and then particularly pointed out in the claims.

In the accompanying drawings, which form a part of this specification, Figure 1 is a plan view of my improved sash-fastener detached. Fig. 2 is a plan of the same in place with the cover removed. Fig. 3 is an end view of a bushing. Figs. 4 and 5 are plan views of escutcheons. Figs. 6 and 7 are side views of the locking-bolts. Fig. 8 is a side view of the bell-crank. Fig. 9 shows a plan of a modification with the covering-plate removed. Fig. 10 represents a sectional side view of part of the fastener with a different form of operating-knob; and Fig. 11 shows a portion of the covering-plate with a different form of slot from that shown in Fig. 2.

Referring now to the details of the drawings, A represents the case, which is of rectangular or any suitable form, and constructed to be attached to the top bar, B, of the lower sash by two screws, one passing through the lug a, and the other passing through both plates of the fixture through holes b b'. (Shown in Figs. 1 and 2.)

C is a metal cover fitting over the top of the

case A, and is secured thereto by a screw, c, passing through both cover and case and forming the axis of the bell-crank F, as will be 55 hereinafter described. This cover is designed to protect the operating parts of the device, and is preferably bronzed to give the fastener an ornamental appearance.

At D is a bolt which projects through the 60 case A, and is designed to enter a hole in the upper sash. It is provided at its other end with a knob, d, by which it may be operated, the shank of which passes through a recess, h, having a notch, i, at each end. 55

E is another bolt, whose nose projects through the side of the case at right angles to the bolt D, and is designed to enter a hole in the side of the window-casing.

F is a bell-crank pivoted on the screw c, 70 which secures the cover to the case. At e e' are recesses in the bolt D, and at f a projection on the inner end of the bolt E. Near the opposite end of the bolt E within the case is formed a shoulder, g. 75

G is a flat spring, preferably of steel, and is set in an angle formed in the case A, as shown. One end of this spring bears against the shoulder g of the bolt E, and the other end on the inner end of the bolt D, as shown in Fig. 2, 80 which spring forces both bolts outward, as will be readily understood.

H is a recess formed in the case A, and is designed for the passage of the window-cord. The casing may have any desired number of 85 holes in the path of the bolt E as the lower sash is raised, and the stile of the upper sash may also have a corresponding or a different number of holes in the path of the bolt D, so that the lower sash may be raised to any desired position, and there engage the casing and upper sash; or the upper sash may be lowered to any desired point and engaged by its bolt; or the lower sash may be raised and the upper sash lowered to a certain extent and there 90 engaged. The bolt E passes under the bolt D, through the recess e' therein, when in operation, and the construction is such that the bolt D may be in place while the lower sash is moved up till the bolt E finds its hole. The 95 holes in the casing and in the stile of the upper sash may be provided with a bushing, (shown in full lines in Fig. 3, and in dotted lines in Fig. 2,) or they may be covered by the

100

escutcheons shown in Figs. 4 and 5, which should be bronzed or nickel-plated to give them an ornamental appearance.

In Figs. 3, 4, and 5 I have shown one style of bushing and two styles of escutcheons, but do not limit myself to any particular style, as it is evident that others would answer the purpose equally as well; or they may be dispensed with entirely.

10 In Fig. 9 I have shown a modified form of my fastener. In this case a round wire spring, G' , is used, which operates only on bolt E, and another spring, G^2 , (preferably a flat one,) presses against the side of the bolt D. With 15 this arrangement of the springs I make the notches in the slot h on the right-hand side of the same, as shown in Fig. 11, so that the tendency of the spring G^2 will be to force the bolt into one of the notches when the shank 20 of the knob is opposite either of said notches.

Instead of the ball-knob shown in Fig. 6, it may be preferable to use a semispherical knob or head, shown in Fig. 10.

The operation of the fastener shown in Fig. 25 is as follows: Supposing the window to be closed and it is desired to have it partially open, it is only necessary to move the knob d along in the slot h , when the bolt D will be withdrawn from its hole in the upper sash.

30 This movement will cause the bell-crank to turn on its pivot, owing to the engagement of one of its arms with the recess in the bolt D, and as this bell-crank turns it withdraws the bolt E from its hole in the casing, owing to the 35 engagement of the other arm of the bell-crank with the projections f on the end of the bolt E. In order to lock the bolts to prevent the possibility of tampering with them from the outside, it is only necessary to move the knob 40 into one of the notches at each end of the throw of the bolt D. It will be observed that the spring G bears on the end of the bolt D, and thus, in addition to its function of pressing in said bolt, it serves also as a friction device,

and thus retains the shank of the knob in the 45 slot h . This is assisted by the curved end of the spring. The same function is served by the spring G^2 ; but the latter also pushes the shank into the slot. If, however, the form shown in Figs 9 and 10 is used, it is unnecessary to move the knob sidewise to lock the bolts, as the spring G^2 will force the shank of the knob d into the notch at the end of the shank, and thus securely lock the bolts in position. It will thus be seen that the sashes 55 can be securely locked at any desired height, and that the operation of locking is performed simultaneously with that of raising or lowering the sashes and by the same mechanism that holds the sashes in place, thus avoiding 60 the expense and inconvenience of an independent locking device for securing the bolts in place.

What I claim as new is—

1. In a sash-fastener, the combination of 65 the bolt D, having recess e , the bolt E, having projection f , the bell-crank F, one arm of which is constructed to engage with the walls of said recess, and the other with said projection, to operate the bolt E in one direction, 70 and the spring G, constructed to operate said bolt in the opposite direction, substantially as and for the purpose specified.

2. The combination, with the bolt E, having projection f , and the bolt D, having recess 75 e , of the bell-crank F, constructed to operate said bolts simultaneously, said bolt D also being provided with a recess, e' , thereby permitting the uninterrupted travel of said bolts on the same plane, and the spring G, operating 80 on said bolts, substantially as described.

In testimony whereof I affix my signature, in presence of two witnesses, this 2d day of September, 1884.

FRANCIS M. CASE.
